YARN TENSIONING AND CONTROL MECHANISM

Montgomery B. Penman, Bloomsburg, Pa., assignor to The Magee Carpet Company, Bloomsburg, Pa., a corporation of Pennsylvania

Filed Mar. 29, 1956, Ser. No. 574,745

12 Claims. (Cl. 242—149)

This invention relates to yarn feeding and control mechanism for multiple tufting machines.

In my prior application, Serial No. 445,768, filed July 26, 1954, now Patent No. 2,898,876, I disclosed a multiple needle tufting machine having means for controlling the feeding of the individual yarns to the needles and it is an object of the present invention to provide tube supporting units for guiding and controlling the feeding of yarns to a large number of needles such as employed in tufting machines for making carpets.

A further object of the invention resides in providing a plurality of yarn guide tube supporting members, each member supporting a plurality of tubes through which the yarns pass leading to the needles of the tufting machine, the supporting members having interfitting engagement with adjacent members but capable of independent removal.

A still further object of the invention resides in compactly mounting a series of yarn guide tubes together with yarn control means for each tube on a supporting member which is independently mounted on the machine and may be readily removed therefrom.

Other objects and advantages of the invention will be apparent during the course of the following description.

In the accompanying drawings forming a part of this specification and in which like numerals are employed to designate like parts throughout the same:

Fig. 1 is a front elevational view of the supporting member for the guide tubes and yarn control means.

Fig. 2 is an elevational view of the one side of the supporting member.

Fig. 3 is an elevational view of the other side of the supporting member.

Fig. 4 is a vertical sectional view taken on line 4—4 of Fig. 1.

Fig. 5 is top plan view.

Fig. 6 is a cross sectional view taken on line 6—6 of Fig. 1.

Fig. 7 is a detail vertical sectional view showing the arrangement of the guide passages in the supporting member.

Fig. 8 is a detail view of the guide passage showing the yarn held against movement, and,

Fig. 9 is a side elevational view of a pair of yarn guide members in operative relation.

Referring to the drawings, the numeral 5 denotes generally one of a plurality of yarn guide tube supporting members, each comprising a metal casting having vertically inclined parallel side walls 6 connected by a vertically disposed panel 7 which is off-set at spaced elevations to provide a series of shoulders 8 in vertical stepped relation. Each off-set portion 7' of the panel is provided with a pair of vertical passages 9 opening through the shoulder 8 and the passages of one off-set portion are arranged in staggered relation to the passages of the next adjacent off-set portion. The upper ends of the passages 9 are enlarged, as at 9', to receive the lower ends of the guide tubes 10 which are suspended from a plate 11 at-

2

tached to the upper ends of the side walls 6 and projecting outwardly therefrom in overhanging relation to the shoulders 8. The plate has a series of openings 12 to receive the flared upper ends 13 of the tubes and a cover plate 14 is removably attached to the plate 11 by screws 15. A series of openings 16 in the cover plate are aligned with the bores of the tubes 10 and the yarns from a source of supply, such as a creel, pass through the tubes and passages 9, there being one yarn for each needle of the tufting machine.

Attached to the outer faces of the side walls 6 are a series of solenoids 17 supported by U-shape brackets 18 and covering the outer ends of the solenoids is a bar 19 spaced from the brackets by collars 20 and attached to the brackets by screws 21. There is one solenoid for each of the passages 9 and the solenoids are positioned so the reduced inner end 22 of the solenoid core 23 is slidably in transverse passages 24 formed in the panel 7 which communicate with and intersect the vertical passages 9. A stem 25 extends from the outer end of the core 23 and projects through openings 26 in the bar 19. Attached to one of the bars 19 is a series of electrical terminals 27 for connecting the circuit wires 28 to the various solenoids, said circuit wires being connected with a pattern controlled circuit making and breaking means such as disclosed in my prior application. Upon energizing of the solenoids the cores move inwardly causing the reduced ends 22 to intersect the bore of the passages 9 and thereby clamp the yarn 29 against the wall of the passage to hold it against movement, as clearly shown in Fig. 8.

In practice there are a series of the supporting members 5, the number depending on the number of needles. The members 5 are supported on suitable cross bars on the tufting machine, with each member in interfitting relation to the next adjacent member but readily removable as a unit when it is necessary to make adjustments or repairs. The tubes 10 of each member fit between the side walls of the next adjacent member with the outermost tubes abutting against the rear wall of the upper most off-set portion of panel 7 and the longitudinal edges of the side walls of adjacent members are in spaced relation. To remove one of the members 5 the means fastening the member to the cross bars is removed and the member may then be lifted upwardly until it is free from adjacent members. To remove the individual tubes 10 from the supporting member the cover plate 14 is removed and the tubes may then be raised upwardly through the openings 12 of plate 11, thus making it easy to replace the tubes if necessary. The arrangement of the tubes insures free movement of the yarns to their respective needles and enables the solenoids for controlling the movement of the yarns through the tubes to be compactly mounted and yet be readily accessible.

It is to be understood that the form of my invention herein shown and described is a preferred example of the same and changes in the shape, size and arrangement of the parts may be made without departing from the spirit of the invention or scope of the subjoined claims.

Having thus described my invention, I claim:

1. A yarn tensioning mechanism for multiple needle tufting machines comprising a yarn guiding member mounted above the needle bar of the machine, said member having a panel formed with a plurality of transverse shoulders in vertical stepped relation to each other, each shoulder having a row of passages extending downwardly through the panel for the passage of yarns, solenoids mounted on the ends of said panel in corresponding stepped relation to said shoulders and plungers operated by said solenoids, said plungers being slidably mounted in openings in the ends of said panel disposed in stepped

relation and intersecting said passages whereby said plungers are movable to grip the yarns.

2. A yarn tensioning mechanism as defined in claim 1 including rows of tubes mounted on said shoulders in alinement with said passages.

3. A yarn tensioning mechanism as defined in claim 1 wherein the row of passages in each shoulder is arranged in staggered relation to the row of passages in the next shoulder.

4. A yarn tensioning mechanism for multiple needle tufting machines comprising a yarn guiding member mounted above the needle bar of the machine, said member having a panel formed with a plurality of shoulders in vertical stepped relation to each other, each shoulder having a row of passages extending through the panel for the passage of yarns, said panel having side walls provided with openings disposed in corresponding stepped relation to said shoulders and intersecting said passages, plungers slidably mounted in said openings for gripping and holding the yarns in said passages and solenoids mounted on said side walls for operating said plungers.

5. A yarn tensioning mechanism of the character defined in claim 4 including rows of tubes mounted on said shoulders in alinement with said passages.

6. A yarn tensioning mechanism for multiple needle tufting machines comprising a series of independent yarn guiding members mounted above the needle bar of the machine, each member comprising a series of parallel rows of tubes for the passage of the yarns, opposed side walls parallel to said rows of tubes, said side walls being inclined to the longitudinal axis of said tubes with one edge extending from the lower ends of the rows of tubes to overlap rows of tubes of the next adjacent guide member, and means mounted along the longitudinal axis of said side walls in stepped relation for gripping and holding the yarns in said tubes.

7. A yarn tensioning mechanism for multiple needle tufting machines comprising a series of independent yarn guiding members mounted above the needle bar of the machine, each member comprising a panel formed with a plurality of shoulders in vertical stepped relation to each other, each shoulder having a row of passages extending through the panel, rows of tubes mounted on said shoulders in alinement with said passages for the passage of the yarns, opposed side walls parallel to the rows of tubes and inclined to the longitudinal axis of said tubes with one edge extending from the lower ends of the rows of tubes to overlap rows of tubes of the next adjacent guide member, plungers slidably mounted in said side walls and panel in corresponding stepped relation.

5 4
tion to said shoulders and intersecting said passages, and solenoids for actuating said plungers to grip the yarns in said passages.

8. A yarn tensioning mechanism for multiple needle tufting machines comprising a yarn guiding member mounted above the needle bar of the machine, said member having a panel formed of off-set sections disposed in vertical stepped relation to each other, each section having a row of vertical passages therethrough for the passage of yarns, and means mounted on the ends of each panel section in corresponding stepped relation to said panel sections and operable to intersect said passages to grip and hold the yarns.

9. A yarn tensioning mechanism for multiple needle tufting machines as described in claim 8 having tubes extending upwardly from the passages in the panel sections.

10. A yarn tensioning mechanism for multiple needle tufting machines as described in claim 8 wherein the rows of passages are disposed in staggered relation.

11. A yarn tensioning mechanism for multiple needle tufting machines comprising a supporting member mounted above the needle bar of the machine having a series of parallel rows of yarn guiding passages through said member and means mounted on the ends of said member in vertical stepped relation operable to intersect said passages for selectively gripping the yarn in said passages.

12. A yarn tensioning mechanism for multiple needle tufting machines comprising a yarn guiding member mounted above the needle bar of the machine, said member having parallel rows of tubes for the passage of yarns, with each successive row of tubes being of a different length, and means mounted on the ends of said member in vertical stepped relation operable to intersect said tubes to grip and hold the yarns passing through said tubes.
